FRANKLIN A. MILLER AND BERTRAND M. TANNER, OF ST. ANTHONY, IDAHO.

COLLAPSIBLE CAMP-BED FRAME.

1,399,363.

Specification of Letters Patent.

Patented Dec. 6, 1921.

Application filed December 28, 1920. Serial No. 433,685.

To all whom it may concern:

Be it known that we, FRANKLIN A. MILLER and BERTRAND M. TANNER, citizens of the United States of America, residing at St. Anthony, Fremont county, Idaho, have invented certain new and useful Improvements in Collapsible Camp-Bed Frames, of which the following is a specification, reference being had therein to the accompanying drawings.

The object of the present invention is to provide a foldable and collapsible camp bed frame which will be strong and rigid when set up but which may be quickly collapsed and folded into a bundle of very small compass if desired.

It is a further object of the invention to provide a bed of the character indicated of such a nature that the usual wire or canvas bed bottom or spring mattress may be employed in conjunction therewith. It is a further object of the invention to provide a bed frame of the character indicated the main portions of which are constructed of angle iron and in such a manner that the structure as a whole may be very economically manufactured.

Further objects and advantages of the invention will be set forth in the detailed description which follows.

In the accompanying drawings:

Figure 1 is a plan view of the hinge construction between the side and end frame members of the bed;

Fig. 2 is a side elevation of the structure shown in Fig. 1;

Fig. 3 is a plan view upon a smaller scale illustrating the overlapping portions of the side frame members;

Fig. 4 is a side elevation of the structure shown in Fig. 3;

Fig. 5 is an enlarged plan view of the overlapping portions of the side frame members;

Fig. 6 is a side elevation of the structure shown in Fig. 5; and

Fig. 7 is an underside view of one of the ends of the frame members illustrating a truss construction hereinafter described.

Like numerals designate corresponding parts throughout the several figures of the drawings.

The bed frame of the present invention comprises ends A, sides B and legs C. The sides B are hinged to the ends A by means of the hinge joint construction illustrated in Fig. 1, it being understood that this con-

struction is duplicated at all four corners of the bed frame. Each of the side frame members or rails B comprises two completely separable angle bars 5 and 6 and when these sections are longitudinally separated from each other, they may swing upon the hinge joints over into parallelism with and against the end members A. Thereafter the legs C may be folded upwardly against the under sides of said end members A and these three parts may be rolled into the wire or canvas bed bottom to constitute a compact bundle, capable of ready transportation and particularly useful for campers, automobilists and the like.

The joints between the sections 5 and 6 of the side rails are constructed as follows: The vertical flange 7 of the angle iron of which the section 6 of the rail is constructed carries a stud 8 that is provided with a head 9, the latter being offset from the vertical flange 7 a sufficient distance to permit of the notched end 10 of the vertical flange 11 of the section 5 being inserted between the head 9 and the flange 7. The horizontal flange 12 of the section 6 is cut as indicated at 13 and this cut portion is downturned to form a lug 14 which enters an opening 15 formed in the horizontal flange 16 of the section 5. By inserting the notched end 10 of the section 5 behind the head 9 of the stud 8 while the sections 5 and 6 are held at an angle with relation to each other and then rocking these two sections downwardly to force the lug 14 into the opening 15, the two sections are securely united against either longitudinal or lateral separation except under the influence of an upward pull by the person who desires to collapse the frame.

The hinge joints at the corners of the bed frame are constructed as follows: The sections 5 and 6 have hinge yokes 17 welded thereto the upper and lower portions of which lie above and below the eyes 18 of hinge plates 19, said hinge plates being welded or otherwise secured to the members A. To further aid in securing the hinge plates 19 rigidly to the members A angle clips 20 have their horizontal portions 21 welded to the under faces of the horizontal flanges 22 of the angles constituting the members A and have their vertical portions 23 welded to the inner faces of the hinged plates 19.

The legs C are pivoted to swing about a

stud 24. The pivot connection between the side rails and the end members A is constituted by a bolt 25 which traverses the upper and lower members of the hinge yoke 5 17 and the eye 18. The horizontal flanges 22 of the end frame members A are provided with holes 26 in which a wire bed bottom 27 of any conventional form is engaged.

In setting up the bed the legs are first 10 brought to an upright position and the side rail sections are then swung outwardly to the position illustrated in Fig. 3. At this time the vertical wall of the hinge yoke 17 will lie flat against the outer faces of the 15 legs and thus will hold the legs securely against collapsing. Further rigidity is imparted to the structure by having the lower horizontal members 28 of the hinge yoke engage in notches 29 formed in the forward 20 edges of the legs. When the legs C are brought to vertical position they are rendered additionally rigid by clips 19^a secured to the outer faces of the hinge plates 19. The meeting ends of the side rail sections 25 may then be united in the manner hereinbefore set forth and the parts will be so proportioned that the act of springing the side rail sections 5 and 6 into parallelism with each other to cause the lug 14 to enter the 30 opening 15 will place the bed bottom fabric 27 under tension.

From the foregoing description it will be seen that a simple and inexpensive construction is herein provided by virtue of which 35 campers, automobilists and the like are not only provided with a bed which may be easily and quickly set up and which will not be in danger of collapsing but, which is equally as important, they will be provided 40 with a bed which is as comfortable as the average permanently constructed bed. There are many camp beds on the market and many of them can be very quickly set up but the most of them are so flimsily 45 constructed that they are incapable of providing a comfortable night's rest for the user.

In Fig. 7 we have illustrated means for 50 imparting additional rigidity and strength to the end members A. In this figure a truss rod 30 has its ends engaged with the vertical flange of the member A. The central portion of this truss rod has a bearing 55 on a short pipe section or boss 31 welded to

the underface of the horizontal flange of the 55 member A.

It is to be understood that the invention is not limited to the precise construction set forth but that it includes within its purview whatever changes fairly come within either 60 the terms or the spirit of the appended claims.

Having described our invention, what we claim is:

1. A bed bottom comprising a pair of 65 completely separable sections, each having a transversely extending end frame member and a pair of longitudinally extending side rails, studs carried by the side rails of one pair, notches formed in the ends of the side 70 rails of the other pair adapted to engage said studs, horizontally overlapping portions upon the side rails of the opposed pairs which limit downward rocking movement of the two sections to a position where 75 the side rails lie in substantial alinement with each other, legs pivotally connected to the end members and adapted to fold upwardly therebeneath and in parallelism therewith and hinge connections between the 80 end frame members and the side rails for permitting the side rails to fold in parallelism with the end frame members, portions of said hinge connections overlying and abutting against the legs when the parts are 85 in assembled relation to thereby hold said legs against movement.

2. A bed bottom comprising a pair of 90 completely separable sections each having a transversely extending end frame member and a pair of longitudinally extending side rails, studs carried by the side rails of one pair, notches formed in the ends of the side 95 rails of the other pair adapted to engage said studs, downwardly projecting lugs upon the ends of the side rails of the one pair and openings formed in the horizontal portions of the side rails of the other pair into which said lugs project when the side rails of the two pairs are brought substantially into 100 horizontal alinement with each other and a spring bed bottom the ends of which are connected to the transverse end members.

In testimony whereof we hereunto affix our signatures.

FRANKLIN A. MILLER.
BERTRAND M. TANNER.
